CLAIM

The ornamental design for the telescoping bicycle, as shown and described.

DESCRIPTION

FIG. 1 is a perspective view of the telescoping bicycle in a first configuration;

FIG. 2 is a front elevational view of the telescoping bicycle;

FIG. 3 is a rear elevational view of the telescoping bicycle;

FIG. 4 is a left side elevational view of the telescoping bicycle in the first configuration, the opposite side of which is an identical mirror image;

FIG. 5 is a top plan view of the telescoping bicycle in the first configuration;

FIG. 6 is a bottom plan view of the telescoping bicycle in the first configuration; and,

FIG. 7 is a perspective view of the telescoping bicycle in a second configuration.
